FIG. 3

UNITED STATES PATENT OFFICE

2,598,650

SNAP LOCK PLIERS WITH UNLOCKING LEVER

Justin L. Smith, Watertown, Conn., and Leif H. Eriksen, Oslo, Norway, assignors to Seymour Smith & Son, Inc., Oakville, Conn., a corporation of Connecticut

Application July 28, 1948, Serial No. 41,064

2 Claims. (CL. 81—84)

1

This invention relates to tools of the plier-wrench type, and more particularly to pliers having an adjustable handle which may be operated by a toggle action to lock the plier jaws.

One object of this invention is to provide a device of the above nature which includes a lever for manually releasing the movable handle from its locked position.

Another object is to provide a device of the above nature which includes indicating means for permitting the jaws to be readily adjusted to any desired size of opening.

A further object is to provide a device of the above nature which will be simple in construction, inexpensive to manufacture, easy to manipulate, compact, ornamental in appearance, and very efficient and durable in use.

With these and other objects in view, there has been illustrated on the accompanying drawing one form in which the invention may conveniently be embodied in practice.

In the drawing,

Fig. 1 is a side view of the improved pliers as it would appear when locked upon a work piece.

Fig. 2 is a similar side view of the same, with certain parts broken away to show the operating mechanism.

Fig. 3 is a side view similar to Fig. 2, but showing pliers in unlocked position.

Fig. 4 is a perspective view of the unlocking lever.

Fig. 5 is a cross sectional view of the same, taken on the line 5—5 of Fig. 4.

Fig. 6 is a cross sectional view taken on the line 6—6 of Fig. 2.

Referring now to the drawings in which like reference numerals denote corresponding parts throughout the several views, the numeral 10 indicates the improved pliers which comprises an elongated stationary handle 11 which is U-shaped in cross section and has a fixed jaw 12 at its front end, and an L-shaped lever 13 which carries a movable jaw 14 in opposed relation to the fixed jaw 12.

The L-shaped lever 13 comprises a flat triangular leg 15 which is swingably mounted within the handle 11 rearwardly of the fixed jaw 12, by means of a pivot pin 16 having headed-over ends, and a forked front leg 17, to which the movable jaw 14 is secured by means of a swivel pin 18.

In order to operate the movable jaw 14, use is made of a movable handle 19 of U-shaped cross section which is connected to the rear corner of the L-shaped lever 13 by means of a pivot

2

pin 20. The movable handle 19 is also connected with the stationary handle 11 by means of a toggle link 21, the front end of which is secured within a central portion of the movable handle 19, by means of a pivot pin 22.

The toggle link 21 has a rounded rear end 23 which is embraced by the rear portion of the stationary handle 11 and is adapted to bear against an adjustable longitudinal screw bolt 24 which is carried in a tapped cylindrical rear end portion 25 of the handle 11, and is provided with a knurled outer knob 26.

It will be noted that when the pliers are locked in clamping position (Fig. 2), the rear end 23 of the toggle link 21 and the pivot pins 20 and 22 will be disposed in substantially a straight line, as shown in Figs. 1 and 2.

In order to prevent excessive inward movement of the movable handle 19 past the locking position, the toggle link 21 is provided with a side lug 27 which is adapted to abut the inner surface of the handle 19. Thus, when the pliers are locked, the pivot pin 22 will occupy a position at or a little inwardly of dead center, and it will be necessary to exert a substantial outward force upon the movable handle 19 in order to unlock the pliers.

The toggle link 21 also is provided with a rounded tapered front nose 28 which is adapted in unlocked position to abut the inner surface of the inner handle 19 so as to limit outward movement of the handle (see Fig. 3).

The rear end 23 of the toggle link 21 will normally be maintained in abutment with the adjusting screw 24 by means of a hook-ended coiled spring 29, engaged through apertures 30, 31 in the handle 11 and the lever 13, respectively, so as to urge the L-shaped lever 13 and the jaw 14 to the unlocked open position.

As a provision for moving the handle 19 outwardly beyond the "dead" point and thus breaking the toggle action of the link 21, use is made of a curved unlocking lever 32 substantially T-shaped in outline, disposed within the rear portion of said handle 19. The unlocking lever 32 is U-shaped in cross section, and is supported by means of a pair of apertured side ears 33, 34 which extend from central portions of its edges and are pivotally secured in recesses 34a in the rear end 23 of the toggle link 21 by means of a headed pivot pin 35. The unlocking lever 32 has a pointed nose 36 at its front end, which is adapted to engage the inner surface of the movable handle 19, and is provided at its rear end 55 with a finger piece 37 which projects rearwardly

3.

slightly beyond a finger piece 38 on the rear end of the movable handle 19, whereby it will be readily accessible to the operator for convenience in manipulation.

By means of this construction it will be seen that the adjusting screw 24 may readily be turned so that the size of the opening between the plier jaws 12 and 14 may be varied as desired. In order to permit the operator to ascertain the size of this opening when the jaws are in their closed and locked position, use is made of a graduated scale 39 marked upon a central side edge portion of the stationary handle 11 adjacent the toggle link 21. An index mark 40 is provided at a suitable central location upon the toggle link 21, so that when the plier handles 11, 19 are in their wide open position, the index mark 40 and the scale 39 will give a correct indication of what the size of the jaw opening will be when the handles are closed in any stage of adjustment of the screw 24.

The scale 39 is provided with a row of numbers to indicate the size of the jaw opening in some uniform standard of measurement, herein shown in inches.

Operation

In use, the operator will first adjust the plier jaws 12, 14 to provide an opening suitable for clamping the work piece W. This will be done by first moving the plier handles 11, 19 to their wide open position, and then rotating the adjusting screw 24 by means of the knob 26 in the proper direction to bring the index mark 40 opposite the proper graduated marking 39 on the handle 11.

The jaws 12, 14 will then be placed over the work piece W after which the handles 11, 19 will be swung together into the position shown in Figs. 1 and 2, whereupon the work piece W will be firmly gripped. In this position, the pivot pin 22 will be located in a line between the rear end 23 of the toggle link 21 and the pivot pin 20, or slightly inwardly of such a line, as determined by the abutment of the side lug 27 with the movable handle 19, and considerable force would normally be required to swing the handle 19 outwardly in order to break the toggle action and release the work piece W.

By means of the present invention, however, this action may be accomplished by a light pressure upon the unlocking finger piece 37, whereby the nose 36 will engage the movable handle 19 with a greater force and cause it to move outwardly from the position shown in Figs. 1 and 2 to that shown in full lines in Fig. 3.

One advantage of the improved snap lock pliers herein disclosed is that it will enable the user to work with greater ease and rapidity, since the unlocking lever will avoid the awkward movements which were formerly necessary to unlock jaws in pliers of this type.

Another advantage is that the indicating scale on the handle will avoid the necessity of adjust-

4

ing the pliers in successive steps by trial-and-error methods.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new and for which it is desired to secure Letters Patent, is:

1. In a snap-lock toggle-grip pliers, a work-clamping jaw carried rigidly on a stationary plier handle of U-shaped construction, a second work-clamping jaw adjacent said first jaw, an L-shaped lever embraced by said handle and pivotally connected thereto and to said second jaw, a movable handle of U-shaped cross-section pivotally connected at one end to said L-shaped lever, a toggle link embraced by both of said U-shaped handles and pivotally connected adjacent its forward end to said movable handle intermediate the ends thereof, said stationary handle having a longitudinal adjustable screw mounted at its rear and engaging the rear end of said toggle link, and a T-shaped unlocking lever embraced by said movable handle and having a perpendicular leg pivotally connected with the rear end of said toggle link, the rear end of said unlocking lever serving as a handle and the forward end of said unlocking lever having a curved pointed section engageable against the central portion of said movable handle.

2. The invention as set forth in claim 1, in which said stationary handle is provided with a graduated scale on the edge of its outer surface and said toggle link has an index mark adjacent said scale to indicate the distance between the jaws when the pliers are in closed locked position.
